UNITED STATES PATENT OFFICE

105,901

DESIGN FOR A KEY CHAIN OR SIMILAR ARTICLE

Arthur J. Schwartz, New York, N. Y., assignor to David P. Barry Corporation, New York, N. Y., a corporation of New York

Application July 17, 1937, Serial No. 70,508

Term of patent 3½ years

To all whom it may concern:

Be it known that I, Arthur J. Schwartz, a citizen of the United States residing at 545 West End Avenue, in the city of New York, county of New York, and State of New York, have invented a new, original, and ornamental Design for a Key Chain or Similar Article, of which the following is a specification, reference being had to the accompanying drawing, forming a part thereof, in which:

Fig. 1 is a perspective view of the article showing my new design; and

Fig. 2 is a perspective view showing the link portion of the article looped and connected at its ends.

I claim:

The ornamental design for a key chain or similar article, substantially as shown and described.

ARTHUR J. SCHWARTZ.
